UNITED STATES PATENT OFFICE.

EMMET H. SCOTT AND JOSEPH FRENIER, OF LA PORTE, INDIANA.

VEHICLE-WHEEL.

SPECIFICATION forming part of Letters Patent No. 276,899, dated May 1, 1883.

Application filed November 20, 1882. (No model.)

To all whom it may concern:

Be it known that we, EMMET H. SCOTT and JOSEPH FRENIER, of the city and county of La Porte, in the State of Indiana, have invented 5 a new and useful Improvement in Wheels, of which the following is a specification.

Our invention relates to improvements in wheels for agricultural implements, traction-engines, thrashing-machines, and wheeled vehicles generally.

The object of our improvement is to provide a wheel of which any part can be readily replaced or renewed, which is light, cheap, durable, and strong, and which can readily and 15 efficiently be constructed entirely of metal.

Our invention is characterized mainly by the combination, with a box or supporting-spindle which can be turned or rotated independently of the spoke-holding devices, of annular 20 castings or spoke-holders mounted on and adjustably connected to said box in such manner that they will approach or recede from one another, according to the direction in which the box is rotated, and independently movable or 25 adjustable spokes, which are held at one end by the rim and at the other end by said castings or holders. By giving the spokes capacity for adjustment independently of one another we can correct inequalities in the length 30 of the spokes and get the wheel well balanced and truly round, while by the adjustable connection between the box and the spoke-holders or annular castings the latter can be caused to simultaneously approach or recede from one another, thus putting simultaneously upon all 35 the spokes the desired tension.

In the accompanying drawings, to which we will now refer, we have represented the preferred embodiment of our invention.

40 Figure 1 is a side view of the wheel. Fig. 2 is a cross-section of the wheel. Fig. 3 is a longitudinal section of one end of the hub, and Fig. 4 is a cross-section of one end of the hub.

45 The hub A consists of three parts, b c c. The middle part, b, is the box or bearing for the axle. c c are annular castings or spoke-holders. Each of these castings is fitted with holes to receive and retain the spokes, the 50 number of spoke-holes in each being one-half of the number of spokes in the wheel. The two sets of spokes are at the hub several

inches apart, thus forming a very strongly-braced wheel which cannot dish. In order to obtain the adjustable connection hereinbefore 55 referred to between the annular castings and the box, the latter has on one end a right-hand screw-thread and on the opposite end a left-hand screw-thread, and each annular casting is internally screw-threaded, so as to screw 60 upon that end of the box for which it is designed. By this construction it will be seen that if the box be rotated and the castings held from following its rotary movement they will be caused to simultaneously approach or 65 recede from one another, according to the direction in which the box is rotated. After the wheel is completed the tension on the spokes will be increased by moving the castings apart, and will be diminished by bringing them nearer 70 together. This can be accomplished by turning the box as above indicated. In many cases a piece of gas-pipe will be a suitable box. There may be a projection or flange, d d, (indicated by dotted lines,) on each of the annular castings, extending beyond the end of the box, to serve as a sand-band or mud-band, and the spoke-holes may be in this portion of the 75 castings. The rim e of the wheel can be made of iron or steel, of half-oval or other suitable 80 shape in cross-section, with holes at equal distances apart to receive the outer ends of the spokes f. Each spoke has one of its ends screw-threaded and its opposite end formed with a head, like a bolt-head or rivet-head. In 85 the wheel shown in the drawings the screw-threaded ends of the spokes screw into the holes in the rim, which are correspondingly screw-threaded.

In putting the wheel together the spokes are 90 passed point first through the spoke-holes in the hub, and are then screwed into the rim until they are drawn with equal and uniform tension, so as to make the wheel well balanced, true, and round, after which the castings c c 95 are adjusted by turning the box b until the requisite degree of tension is obtained.

In lieu of fastening the spokes as just described, the arrangement may be reversed by having the holes in the rim countersunk to receive the head ends of the spokes and the holes in the annular castings tapped to receive the screw ends of spokes. Then the heads of the spokes would be in position in the rim, and

the screw ends would be screwed into the holes tapped in the annular castings. Either mode of fastening effects substantially the same result; but we prefer on the whole the arrangement shown in the drawings. The spokes at one end of the hub should not be opposite those at the other end, but should alternate with them.

When a wheel is constructed in this manner it acts on the principle of a truss. Ordinarily no other tire than the rim will be necessary. By substituting a spindle for the box *b* and securing the annular castings in place by means of a right-hand thread for one and a left-hand thread for the other cut on the spindle, the castings also being provided with threads to match, or by means of set-screws screwed into the annular castings and binding tight onto the spindle, or by means of double jaw nuts to fit the threads on the spindle to secure a proper adjustment of tension, or otherwise, the wheel may be so modified as to adapt it to use for grain-drill, hay-rake, or wheelbarrow wheels, or any other wheel where it is desired to have the axle turn with the wheel. The hub may also be modified so as to adapt it to a tapering spindle.

What we claim as new, and desire to secure by Letters Patent, is—

1. The combination of the box, the two annular spoke-holders or castings mounted ad-

justably thereon, so as to be capable of being caused to simultaneously approach or recede from one another, the rim and the spokes adjustably connected independently of one another to the annular castings and the rim, substantially as and for the purposes hereinbefore set forth. 35

2. The hub consisting of the right-and-left-screw-threaded box *b* and the end annular castings, *c*, mounted and capable of adjustment thereon as described, in combination with the rim and the spokes having a head at one end and a screw-thread at the other, engaging the rim and the annular castings, respectively, substantially as and for the purposes hereinbefore set forth. 40

3. The right-and-left-screw-threaded box and the annular castings mounted upon said box, so as to project partly beyond the ends of the same, and provided in said projecting parts with spoke-holes, in combination with the rim and the spokes screwed at their outer ends into holes in the rim and held to the castings by heads on their inner ends, substantially as 45 and for the purposes hereinbefore set forth. 50
